ARTICLE PACKAGING DEVICE

George C. McKoy, Atlanta, Ga.

Application December 12, 1947, Serial No. 791,323

4 Claims. (Cl. 93—2)

1

My invention relates to article packaging devices and more particularly to a coin packaging device designed to facilitate the packing of coins in the conventional paper wrappers now in common use, whereby the coins may be easily handled and readily counted.

An object of my invention is to provide a convenient tool for wrapping coins.

Another object of my invention is to provide a coin packaging device adapted to make use of the conventional paper wrappers now in common use.

Another object of my invention is to provide a coin packaging device which is hand operated and substantially automatic in use.

Another object of my invention is to provide a coin packaging device which will make a uniformly neat and attractive package.

Another object of my invention is to provide a coin packaging device which is small, compact, of self-contained unitary construction, and which can be easily carried in the pocket of the user.

Another object of my invention is to provide a coin packaging device which is rugged and simple in construction, efficient and uniformly satisfactory in service, easy and inexpensive to manufacture, and pleasing and attractive in appearance.

All of the foregoing and other and further objects and advantages of my invention will be apparent from the following description taken in connection with the accompanying drawing in which like characters of reference designate corresponding parts throughout the several views, and wherein:

Figure 1 is an isometric view of the disassembled parts of my coin packaging device.

Figure 2 is a side view of my device with coins and a wrapper inserted, ready for packaging.

Figure 3 is an end view taken along the line 3—3 in Figure 2.

Figure 4 is an isometric view of a coin wrapper showing a sealed or crimped end.

The body of the device comprises a tubular casing 10 which is provided with a longitudinal slot 11, into which the wrapper is inserted, and a notch 12 to facilitate removal of packages from the casing. The tubular casing 10 is rolled or turned down or otherwise contracted as at 13 for attachment to a knurled operating head 14. The head 14 has a shank portion 15 which extends into the casing 10 and is provided with an annular recess 16 into which the casing is fastened by rolling, crimping or otherwise as above described. The shank 15 is provided with

2

a longitudinal slot 17 for receiving a sweep or blade 18 and causing it to rotate with the operating head 14. The blade 18 may be more or less permanently attached to the shank 15, or longitudinal movement between the blade and the shank and dislodgement of the blade may be prevented by means of a detent 19 which extends into an annular groove 20. The shank 15 is provided with a reduced portion 21 to provide space for the wrapper 22, and the blade 18 is offset as at 23 to provide space for the wrapper between the blade and the casing 10.

In use, the coins 24 to be wrapped are inserted into the casing 10 until it is filled. It will be understood that the diameter and the length of the casing are determined by the size and number, respectively, of coins to be packaged. The conventional wrapper 22 is then inserted into the slot 11 and beneath the blade 18 so that it rests between the blade 18 and coins 24, as shown in Figure 2. When the edge of the wrapper 22 abuts the bottom of slot 11, the wrapper will then extend a suitable distance beyond each end of the column of coins to be wrapped, as shown in Figure 2.

Operation of the device is simple and substantially automatic. With the casing 10 filled with coins, and a wrapper 22 in place as above described, wrapping is accomplished simply by turning the knurled head 14 in a clockwise direction, whereupon blade 18 advances to the edge of slot 11 which then folds the protruding portion of the wrapper 22 back over the blade 18 as it advances and the wrapper is pulled into the casing and wrapped tightly around the coins as the head 14 continues to be rotated.

When the wrapper has been completely rolled around the coins, the portion of the wrapper projecting beyond the open end of the casing 10 is closed or sealed by crimping, as shown at 25 in Figure 4, and the package may then be removed from the device, whereupon the other end of the package may be sealed, as by crimping. The notch 12 may be of assistance in removing the package from the device if it does not slide out readily when the open end of the casing 10 is lowered.

It will be understood that my device can be made of metal, plastic or other suitable material or materials, that it can be made in various sizes to accommodate various sizes of coins, checks or other articles, and that many changes may be made in details of construction without departing from the scope of my invention as defined in the following claims.

I claim:

1. An article packaging device comprising a tubular casing which is slotted longitudinally to receive a wrapper, a rotary head operably positioned adjacent one end of said casing, said head having a shank portion extending within said casing, an annular groove in said shank to which said casing is fastened, a blade carried by said shank for rotation within said tubular casing, a longitudinal slot in said shank for receiving said blade and causing it to rotate with said head, a detent on said blade for cooperation with said shank to prevent longitudinal dislodgement of said blade, said blade being provided with an offset to afford space between said blade and the interior of said tubular casing.

2. An article packaging device comprising a tubular casing which is slotted longitudinally to receive a wrapper, a rotary head operably positioned adjacent one end of said casing, said head having a shank portion extending within said casing, a blade carried by said shank for rotation within said tubular casing, a longitudinal slot in said shank for receiving said blade and causing it to rotate with said head, a detent on said blade for cooperation with said shank to prevent longitudinal dislodgement of said blade, said blade being provided with an offset to afford space between said blade and the interior of said tubular casing.

3. An article packaging device comprising a tubular casing which is slotted longitudinally to receive a wrapper, a rotary head operably positioned adjacent one end of said casing, said head

5 having a shank portion extending within said casing, a blade carried by said shank for rotation within said tubular casing, a longitudinal slot in said shank for receiving said blade and causing it to rotate with said head, fastening means on said blade for cooperation with said shank to prevent longitudinal dislodgement of said blade, said blade being provided with an offset to afford space between said blade and the interior of said tubular casing.

10 4. An article packaging device comprising a tubular casing which is slotted longitudinally to receive a wrapper, a rotary head operably positioned adjacent one end of said casing, said head having a shank portion extending within said casing, a blade carried by said shank for rotation within said tubular casing, said shank being arranged for receiving said blade and causing it to rotate with said head, and said blade being provided with an offset to afford space between said blade and the interior of said tubular casing.
